UNITED STATES PATENT OFFICE.

THEODORE F. FITZSIMONS, OF STANMORE, NEAR SYDNEY, NEW SOUTH WALES,
AUSTRALIA.

CAN-BODY-ENDING MACHINE.

1,422,192.

Specification of Letters Patent.

Patented July 11, 1922.

Application filed July 2, 1919. Serial No. 308,189.

To all whom it may concern:

Be it known that THEODORE FITZROY Fitzsimons, of 60 Cambridge Street, Stanmore, near Sydney, New South Wales, Australia, 5 subject of the King of Great Britain and Ireland, has invented certain new and useful Improvements in Can-Body-Ending Machines, of which the following is a specification.

10 This invention relates to automatic machines for setting ends (bottoms and heads) on can bodies and securing them thereto by crimping and pinching the seams, which are subsequently sweated or soldered when it is 15 necessary to ensure a hermetic closure of the contents of the can. The invention is primarily applicable for ending cans of rectangular section and is illustrated in the accompanying drawings arranged for that 20 purpose, but it is readily susceptible of mechanical modification to fit it for ending can bodies of circular, elliptical or polygonal section.

The invention includes also mechanism for 25 feeding ends from a stack filled into a hopper so that said ends will be delivered out of the hopper one by one into an ending machine in timing with the movements of the ending devices.

30 The two ends are fitted to the bodies simultaneously. The bodies, which have been formed and side seamed in a preceding operation, are carried through the ending machine sidewise and horizontally by a chain 35 belt which receives intermittent forward motion timed with the movements of the end feeders and the end closing devices. The feeders are arranged to deliver the ends edge- 40 wise into guideways which bring them into alignment with an open body which is located by a cradle in register with a pair of anvil blocks and a group of vise jaws, said 45 anvil blocks and vise jaws being mounted on slides at either side of the machine in which they move bodily inwards carrying the ends onto the bodies, and in which they move bodily outwards after the ends have been pinched into the bodies by a closing movement of the vise jaws. Immediately before reaching the 50 aligning cradle the edges of the bodies are engaged by two press pads which are caused to embrace them and apply a film of a soldering flux where the body part will be pinched in the seam groove in the ends.

55 In the accompanying drawings, Fig. 1 is a

vertical longitudinal sectional elevation of the machine; Fig. 1^a is a fragment showing the feed keys in the feeder chutes by which the accurate timing of the feed of the ends is ensured; Fig. 2 is a sectional plan of the 60 machine omitting duplicated elements on one side of it; Fig. 3 is a fragmentary elevational view of the cam and lateral lever by means of which the anvils and vises are traversed to carry the ends onto the 65 bodies; Fig. 4 is an elevational view of one of the closing heads comprising a four jaw vise and an anvil for rectangular body cans; Fig. 5 is a fragment transverse section through one of the closing heads showing its 70 structural relation to its end feeder and to the body cradle; Fig. 6 is a broken elevational view of the four jaw toggle crank by which closing movement is applied to the four jaws of the vise simultaneously; Fig. 7 75 is a fragment section showing the relation of a toggle, the toggle crank, a vise jaw, and the jaw adjuster screw; Fig. 8 is an enlarged fragment view showing the stripping plunger in advanced position (in Fig. 5 this element 80 is shown in the free or retired position); Fig. 9 is a transverse section on the plane 9—9 Fig. 8; Fig. 10 is an enlarged fragment view explanatory of the feeder operating linkage; Fig. 11 is a broken elevational view 85 suggestive of an alternative device, to take the place of the toggle crank (Fig. 6), for the purpose of closing the vise jaws; Fig. 12 is a transverse vertical section on the line 12—12 Fig. 13 with the parts in idle position; Fig. 13 is a horizontal section on line 13—13 Fig. 12; Fig. 14 is a broken sectional elevation showing certain of the feed mechanism as it appears at the moment of delivering a can end from the hopper; and Fig. 15 90 95 is a broken fragment view of certain parts of the feed mechanism.

A box base 20 carries the ending machine elements, and a table frame 21 built thereon carries the two end feeder elements. The 100 bodies 22, open at either end are fed manually or mechanically sideways into the gravity race 23 down which they slide in contact by gravity to the straight race 24. The sides and tops of the races 23 and 24 105 are constructed of bars 34 in order that the movement of the open bodies and the ended bodies proceeding therethrough may be observed by the machine operators. A feed belt comprising an endless chain 25 carry- 110

ing equally spaced push claws 33 runs in a groove in the bed of the straight race 24, over a driving sprocket wheel 26 and over two idle superposed sprockets 27 and 28, the bed of the race 24 being slotted at 29 and 30 for belt clearance. The drive sprocket 26 receives intermittent motion in the direction indicated by the arrow. Owing to the angular disposition of the gravity race 23 in relation to the straight race 24, a clearance space 31 is always found at the rear of the last body 22 which has passed into the straight race 24. This angular clearance space permits the chain claws 33 to pass up behind said body 22 and thereafter push it along the race 24, the next open body 22 in order then passing by gravity into the "ready" position, where it will be similarly taken hold of by the next claw on the feed belt. To prevent crowding of the down-coming bodies in the gravity race 23, a trap lever 123 with spring knuckle end 124 is pivotally mounted on the bed 20 at 125; its tail 126 is provided with a roller 127 against which a cam 128 on the shaft 36 acts to cant the lever and withdraw the spring knuckle 124 in proper timing to free the can body next behind it as soon as the preceding body has passed into the straight race. 129 is a contracting spring acting on the lever 123 to cant it when it is released by the cam 128. In the first forward movement in the straight race, the open body is 35 brought into register with the opposed pads 60 which are then advanced towards each other so as to press onto the body edges and apply to them a film of flux, which done, the pads are immediately retired. In the 40 next forward movement the body with its edges flux coated as just described is brought to register with the opposed closing heads, the centreing device raised, and the ends forced on and crimped to embrace the body 45 edges. Thereafter the ended bodies move step by step along the straight race and are finally delivered out of the end of it into a slide or are permitted to fall into a receptacle.

50 35 is the driving pulley and 36 the driving shaft. A crank disc 37 on the end of the shaft 36 carries a crank pin 38 which operates a rocker arm 39 by means of a pitman rod 40. This arm 39 is carried freely 55 on the axle 41 of the chain sprocket wheel 26, and it is provided with a catch pawl 42 adapted to engage a detent wheel 43 which is keyed to the axle 41. The parts are proportioned so that the stroke of the 60 pitman rod applies the required angular movement to the wheel 26 to advance the feed belt one step in the progressive movement of the cans from place to place in the ending operation. 130 is an adjustable 65 friction brake which functions to prevent

over-running of the axle 41 when it is actuated by the pawl and detent motion. A face cam 44 on the shaft 36 acts against a roller 45 on the rocking lever 46 which effects the traverse movements of the 70 headers, an edge cam 119 acts against a roller 118 on the arm 117 which operates the four jaw toggle crank 61, and an eccentric 50, also on the shaft 36 acting through a link 51, applies oscillating movements to 75 a beam 52 which is linked as at 53 to a crosshead 54 on a jump rod 55 which is provided at its top end with a slotted head 56 in which the pins 57 on the end of the two feeder levers 58 work.

The cam 63 on the shaft 36 acts against a roller 64 on the tail end of the rocking beam 65, which is fulcrumed at 66, and carries on its outer end through a link 67 a saddle 68 having four upwardly projecting pins 69 arranged to slide through apertured guides 70 on the race table 24. The upper ends of these pins 69 are chamfered off as shown to provide an easy entry at either side of a can body. Their function 80 is to operate as a fence on either side of the can body to hold it in correct register-position for the ending and end closing operation in alignment with the closing heads. The cam timing is arranged so that the pins 95 69 are pushed upwardly (see Fig. 1) as soon as the body has been brought to register position by the belt movement. Except during the period in which the closing heads come into operation, the pins 69 are retired 100 leaving a clear bed. The chain belt 25 is located midway on the bed of the race 24 so that it runs between the pairs of pins 69 and is not interfered with thereby. It is to be observed that there is a feeder at either 105 side of the machine. In Fig. 10, 71 is the magazine of one of these feeders. Each feeder operates to deliver ends 72 (Fig. 5) into a vertically disposed guideway 73 in the closing head located immediately below it. There are two closing heads, one on either side of the machine, each served by a separate feeder as aforesaid. The ends 72, upon dropping edgewise into the guideway 73, are intercepted by the stop feed 110 pins 74 and 75. These pins slide in bearings formed in pads 76 in the side of the guideway 73, and they are connected by links 77 to an oscillating lever 78 which is connected by a link 79 to a bell crank 115 80. The tail end of this bell crank is fitted with a roller 81 located above the straight race 24 and permitted to drop a short distance into said race through a clearance in the top casing thereof. A push link 82, the lower end of which is pivoted on the pin which carries the roller 81, is extended upward to connect with an element 120 in the feeder by which the feeder movements are governed to ensure the delivery 125 130

of one can end to each head each time the bell crank 80 is reciprocated. Reciprocating movement is applied to the bell crank 80 by the contact of the bodies passing through 5 the race 24 with the roller 81 whereby the said roller is lifted as each can body passes under it, with the result that the feeder is operated to deliver another can end into the chute 73 and the lever 78 is 10 reciprocated to alternate the positions of the pins 74 and 75. If there should be a miss in the feed of bodies, the bell crank 80 will not be reciprocated when the un-occupied chain claw is passing below it, 15 and consequently the pins 74-75 will remain idle and the delivery of body ends from the feeder will be interrupted. In the normal idle position of the bell crank 80, which is shown in Fig. 1, the lower pin 20 75 is in the inner position, so that it takes under the lowest end *a* contained in the guideway 73, holding said end therein so that it does not drop into the header. When the pin 75 is in this position the pin 74 25 is retired. As a can body passes under the roller 81, the end *a* is permitted to fall into the header as soon as the pin 75 has been sufficiently retired to remove the support which it offered below said end, 30 but slightly prior to the release of the end *a* the upper pin 74 has been forced inward (as shown in Fig. 1^a) and takes below the following end *b*, supporting it as soon as the can body holds the roller 81 35 upward. As soon as the roller 81 is released by the can body the position of the pins 74 and 75 is alternated, with the result that the end *b* drops into the lower-most position previously occupied by the end *a* and is there supported by the lower pin 40 75 ready for delivery into the header. The headers are laterally movable on transverse guide tables 83. They each comprise a body portion 84 to which reciprocating motion is applied. This body portion carries 45 the closing and stripping mechanism. Reciprocating motion is applied, to the headers as before stated, through the rocking levers 46. The knuckle ends 85 of these levers 50 take against the heads 86 of adjustable studs 87. These studs permit of exact adjustment by screwing them more or less into the header body and fixing them with binding nuts, so that the traverse applied 55 to the headers through the levers 46 is precisely that required for pressing home the ends firmly and holding them in home position on the body rims during the pinching and closing process which is performed 60 by the vise jaws. As the ends 72 fall into the register position they are received in a frame 88, the recessed upper part of which forms the guideway 73. The slot 89 in front of this guideway enables the opera- 65 tor to view the downward procession of ends 72 through the race in the frame 88. The bottom part 90 of the frame 88 is chamfered on the edges so as to eliminate risk of tripping of sharp irregular edges of the ends. An anvil block 91 seated in 70 a pocket in the header body 84 is shaped to fit exactly in the recessed portion of the end, thereby to form an anvil on which the seam edge of the end may be closed over the body rim. When traverse move- 75 ment is applied to the header 84, the anvil 91 is brought up against the back of the end and forces the end on to the edge of the can body, which in Fig. 5 is marked 92. Immediately thereafter the four vise 80 jaws 93, which are formed on their faces complementary to the edge shape of the anvil 91, are closed in, thereby pinching the end rim on the body edge and making a tight mechanical joint. This done, the 85 vise jaws immediately open, and the header body 84 is retired on the guide table 83. The central position of the ended body in the race is, however, maintained by operation of the strippers. These comprise a 90 plunger 94 which is pocketed in the anvil 91 with its spindle extending rearward. A helical spring 95 on said spindle operates normally to pull it backward and so bring the stripper into the recess in the anvil 95 91. The stripper is locked in the traverse position temporarily by the mechanism shown in Figs. 5 and 8. Fig. 8 shows it in the advanced position holding the ended body temporarily in central position in the 100 race 24 so that as soon as the strippers are retired the progressive movement of the body through that race may be accomplished without risk of fouling the body 105 ends in any part of the heading devices. 105

The rear part of the plunger 94 is notched as shown at 96 to engage a trip tooth 97 on the end of a trip lever 98 which is pivotally mounted at 99 on a bridging member 99^a mounted on the guide table 83. The spring 110 115 pressed plunger 100 acts on the rear end of the trip lever 98, and an additional spring 101 may be provided under the inner end of said trip lever, both springs operating to push the tooth upward, so that when it comes into register with the notch 96, during advancement of the header body it will engage same and prevent the retirement of the plunger 96 by means of the spring 95 120 and so hold the stripper head outward in 120 the can engaging position shown in Fig. 8. The tappet screw 102 on the back end of the lever 98 is tripped by contact of the header body with it when it is nearing its retired position. In its contact the lever 98 is 125 tripped upward so that its tooth 97 is released from the notch 96, thus leaving the spring 95 free to operate and withdraw the stripper to the position shown in Fig. 5. A helical spring 104 is contained in the tele- 130

scoping box 105 set between the opposed headers; it operates to push the headers apart but to permit them to be advanced inward for the heading operation when the 5 levers 46 mount the cams 44.

The vise comprises four jaws 93 arranged to slide in a cruciform guideway 106 which is formed with appropriate slides to ensure the movement of the jaws in exact alignment and sufficient clearance is allowed where the jaws meet in the inward movement to allow them to contract sufficiently to ensure effective closing of the same. Each 10 jaw is separately adjustable by means of a tommy screw 107 which passes through a pin 108 on the inner member 109 of the toggle. The outer toggle link 110 is pin mounted at 111 in the cruciform frame 106. The knee pin 112 of each toggle is fitted with 15 a square bush 113 and said bushes work in slot jaws 114 in the four jaw crank 61. The collar 115 of said crank is rotatably mounted on the ring portion 116 of the header body 84. The tail lever 117 of the 20 crank 61 is provided with an anti-friction roller 118 which is engageable by the edge cam 119 on the shaft 36, and is fitted with a retiring pull spring 131 which functions to swing the lever 117 down to bring the 25 roller 118 against the face of the cam 119. Once in each rotation of the shaft 36 the arm 117 is lifted by the tappet action of the cam 119, with the result that the four toggles are straightened and the four vice jaws 30 forced inward. It is obvious that the several cam positions must be determined in correct timing to ensure the orderly sequential movement of the parts.

As an alternative means for forcing in 40 the vise jaws there may be substituted for the toggle motion a wedging device comprising a disc 120 having a tail piece 117 corresponding with the tail piece similarly numbered in connection with the four jaw 45 crank. In the disc 120 are four crank slots 121 disposed angularly in relation to the centre of the disc. In these slots finger pins 122, which are offset from the vise jaws work when a partial rotational movement 50 is applied to the ring 120; the slots 121 sliding over the pins 122 cause the vise jaws to close or open respectively according to the direction of the movement.

The ends, nested more or less closely together or loosely separated as received from the end pressing machines are deposited in the hopper 71, said hopper being in all cases dismembered to correspond with the dimensions of the ends required to be fed. At 55 131 the lowermost end in the pack contained in the hopper 71 is shown supported on the platform forks 132—132, which are capable of endwise motion laterally of the feed throat 137 in the floating bearing pockets 60 133—133 at either side of the machine. Hel-

ical springs 134 rearward of each of these platform forks normally hold them in the carrying position shown in Fig. 12. Centrally, each fork 132 carries a roller 135 positioned to bear against a ramp face 136 at 70 the back of the delivery throat 137 of the feeder. The elevating frames 170 are movable vertically bodily in slide-guides 138 and are normally held upward, as shown in Fig. 12, by helical carrier springs 139. Plungers 140 at either side of the machine connected by links 141 to oscillating beams 58 receive vertical reciprocating motion from a pitman 55, which is driven in timing with the ending machine to which the feeder is 80 fitted. The lower ends of these plungers contact at 146 with the top part of the bearing pockets 133 in the floating frames 170 when the plungers are descended about a quarter of an inch, and when the plungers 85 are moved further downward they force the floating frames 170 downward carrying with them the forks 132; at the same time the forks 132 are retired, the retiring movement being caused by the running of the rollers 90 135 down the ramp faces 136. Above the carrier forks 132, a rubber pad 144 is provided at either side of the hopper; these rubber pads are mounted on the lower ends of hanging links 145 which are fitted with 95 springs 130 arranged to push the hanging links 145 outward, and thus move the rubber pads 144 outward. The links and rubber pads are forced inward by the contact of rollers 147 on the plungers 140 against the 100 ramp faces 148 on the lower part of the links 145. 150 are picker fingers, two at either side of the hopper mounted on pins 151 which are carried in the floating frame 170. They are under constant pressure of 105 backing springs 159 which operate to force their points into the pack of ends, and they are provided each with a bearing roller 152 which co-acts with offset striker pins 157 on the plungers 140 and with the inner faces 110 of the rocking shoes 160, when said shoes are set inward by canting them on their pivots 164 by means of the cross connected crank arms 162 which are connected by an arm 161 and rod 82 to the tappet 81. 154 are push 115 buttons normally held outward by helical spring 155. These buttons are located a little below the top surface of the forks 132 when the bearing pockets 133 are in the upper position.

In the operation of the feeder a pack of ends being set in the hopper 71 and timed reciprocating motion being applied to the oscillating beams 58, the plungers 140 are reciprocated. At top stroke their lower ends 125 set above the fork bearing pockets 133, the links 145 hang outward under pressure of the springs 130, and the faces of the rubber pads do not project within the interior surface of the hopper walls. The pack of ends 130

then rests on the forks 132, (see Fig. 12). As the beams 58 oscillate downward, the plungers 140 are forced downward. The rollers 147 acting against the ramp faces 148 force the links 145 and the rubber pads 144 thereon inward, causing said pads to embrace the lower end of the pack on opposite sides. At the same time, the offset pins 157 are released from contact with the 10 under sides of the offset rollers 152 on the tails of the picker fingers 150, and permit the springs 159 to force said picker fingers forward and set them between the formed edges of the lowermost end in the pack and 15 the edges of the end overlying it. The downward motion still continuing, the picker fingers push the lowermost end downward till it snaps past the push buttons 154. Simultaneously the forks 132 are retired and 20 the released end being then unsupported below, drops down through the feeder throat 137 and striking an angular canting plate 171 is turned on its edge and delivered edge-wise by gravity into a receiving place in the 25 body ending machine with which the feeder is associated. In the return motion, the forks 132 first advance, then the picker fingers 150 retire, and then the rubber pads 144 retire, leaving the pack to settle itself 30 again by gravity, on the forks 132 as the oscillating beams attain top position. 156 is a stop engageable with a shoulder 156^a for regulating the range of upward movement of the floating frames 170.

35 The lever control 82—161 is made automatic by connecting the rod 82 to the tappet 81 which is moved when a can body strikes it whilst moving to the "ending" position in said machine. If a miss has occurred in 40 the feeding in of the bodies the tappet movement does not occur and the lever 161 remains in the lower position. In the lower position of the lever 161 the rocking shoes 160 are canted inward under the tail rollers 45 152 and hold the picker fingers 150 from contacting with the stack of ends in the magazine; consequently feed of ends is interrupted. When the lever 161 is moved to the upper position by means of a hand control or by means of the ending machine tappet 81, the faces of the rocking shoes 160 are brought to the position shown in Fig. 14. In that position they leave the offset rollers 152 free and permit the picker fingers 150 50 to be inserted between the lowermost end in the stack and the end next above it when the striker pins 157 on the plungers 140 release them.

What I claim as my invention and desire 60 to secure by Letters Patent is:—

1. In a can ending machine of the type herein described provided with a race-way, the combination with an anvil, a laterally movable header body supporting said anvil, 65 of a normally retired stripper plunger, a

trip pawl arranged to hold the stripper outward until the retiring movement of the header body is nearing completion and thereupon to release the stripper and so leave the completed can centred in the race-way. 70

2. In a can ending machine of the type described, an end seam closing device including an anvil adapted to set into a can end positioned on a can body and brought to register with said anvil, an intermittently 75 moving can feeding belt, a crank plate, a cam adapted for rocking said crank plate, a cruciform guide, opposed seam closing vise jaws slidable in said cruciform guide in diagonal relation to said anvil, toggle links 80 connecting said cruciform guide arms on said cruciform guide and said sliding jaws respectively, and means for symmetrically adjusting said jaws in relation to said anvil. 85

3. In a can ending machine of the type described, a slide raceway, an intermittently moving body carrier belt, a saddle supported below said belt, centering pins on said saddle, said saddle being adapted to move said pins 90 vertically upward through guide holes in said raceway to lightly embrace can bodies, and a header device including jaws located adjacent the centering pins whereby the latter retain the can bodies in the location symmetrical in relation to the relation of the jaws. 95

4. A heading device for a can ending machine, comprising a body, means for moving the body to and from can engaging position, 100 an anvil seated in said body and adapted to the interior shape of the formed end, a plurality of opposed vise jaws, means for closing the same after the body has moved to can engaging position, a stripper plunger working through the anvil, a retiring spring on said plunger, a pivotally mounted trip pawl, means on the plunger adapted to co-act with the pawl and hold the stripper plunger advanced and means for tripping said pawl. 105 110

5. A can body ending machine including a race-way, conveying means for advancing can bodies sidewise in step by step movement through the race-way, a drive shaft, a traversing mechanism for delivering ends to the 115 can bodies, means on said shaft to actuate said mechanism, a clamping mechanism, means on said shaft to actuate the clamping mechanism, a can end feed mechanism and means on said shaft for actuating said can 120 end feed mechanism.

6. Mechanism for feeding can ends from a stack in single file into an ending machine, comprising a vertically disposed magazine provided with a ramp face an opposed pair 125 of links pendent in the sides of the vertically disposed magazine provided with cam faces, rubber pads in the faces of said links adapted to embrace the lower part of a stack of ends contained in said magazine, plungers 130

- reciprocated in feed timing, means on said plungers adapted to act against said cam faces to force the links inward when the plungers are down, and to release them when the plungers are raised, vertically movable guide frames, spring-pressed carrier forks horizontally slidable in said guide frames, means on said forks co-acting with the ramp faces on the magazine casing and thereby 10 operative to withdraw said forks when said frames are forced downward, with the plungers, spring backed picker fingers adapted to engage between the lowermost end in the pack and the end next above it, push buttons 15 projecting into the magazine below said picker fingers, and tappets on said plungers operating to effect the retirement of said picker fingers during the upward movement of the plungers.
- 20 7. In an end feeder of the type claimed in claim 7 hereof, the combination with elements therein set forth of control means for rendering the feed of ends inoperative without stopping the machine, said means comprising rocking shoes adapted to engage the picker fingers and hold the same out of engagement with the stack of ends, said shoes being link connected to control means actuated automatically by a connection from an 25 ending machine.
8. A can end feeding mechanism associated with an ending machine, and operating to deliver ends in single file from a hopper into said machine, comprising a vertically 30

disposed magazine adapted to carry a stack 35 of ends, gripping pads closable against the stack of ends to carry same in said magazine whilst they are otherwise unsupported therein, picker fingers adapted to separate the lowermost end in the stack from the ends 40 above it, and force it downward independently of the overlying ends, push buttons in the sides of the magazine and reciprocable carrier forks operating through the sides of the magazine under said stack, means operating said picker fingers to move the lowermost end downwardly past said push buttons and permit its delivery by gravity, means for retiring the forks during delivery of the end, means for advancing the gripping pads to 45 operative position during retirement of the forks, and means for restoring the picker fingers to inoperative position.

9. In an ending machine, a can end feeding mechanism comprising a magazine adapted 55 to receive a stack of can ends, means for stripping the lowermost can end from the stack, means for supporting the stack during stripping operation of the lowermost end, means acting to retard the delivery of the 60 stripped end, said retarding means being functionally interrupted by the can end during its advancement by the stripping means, and means for supporting the stack of can 65 ends subsequent to their release by the first mentioned supporting means.

In testimony whereof I affix my signature.
THEODORE F. FITZSIMONS.
